UNITED STATES PATENT OFFICE

157,932

PITCHER OR SIMILAR ARTICLE

Robert Y. Allen, Encino, Melvin Shaw, Beverly Hills, and Evan K. Shaw, Los Angeles, Calif., assignors to Metlox Manufacturing Company, Manhattan Beach, Calif., a corporation of California

Application March 29, 1948, Serial No. 145,424

Term of patent 7 years

(Cl. D44—21)

To all whom it may concern:

Be it known that we, Robert Y. Allen, residing at Encino, in the county of Los Angeles, State of California, Melvin Shaw, residing at Beverly Hills, in the county of Los Angeles, State of California, and Evan K. Shaw, residing at Los Angeles, in the county of Los Angeles, State of California, have invented a new, original, and ornamental Design for a Pitcher or Similar Article, of which the following is a specification, reference being had to the accompanying drawing, forming part thereof, in which:

Fig. 1 is an elevational view of a pitcher or similar article with a handle and accompanying surface decoration showing our new design; and

Fig. 2 is a top plan view thereof.

The dominant features of the design reside in the portions shown in full lines. The side of the illustrated pitcher opposite from that seen in Fig. 1 is free from surface decoration, and the visible portion of the opposite side of the handle has the same appearance as that of the near side shown in Fig. 1.

We claim:

The ornamental design for a pitcher or similar article, as shown and described.

ROBERT Y. ALLEN.
MELVIN SHAW.
EVAN K. SHAW.
